UNITED STATES PATENT OFFICE.

JOHN C. LINCOLN, OF CLEVELAND, OHIO, ASSIGNOR TO THE LINCOLN ELECTRIC COMPANY, OF CLEVELAND, OHIO, A CORPORATION OF OHIO.

METHOD OF AND APPARATUS FOR PRODUCING SPARKLESS COMMUTATION.

1,244,518.

Specification of Letters Patent.

Patented Oct. 30, 1917.

Original application filed February 2, 1912, Serial No. 674,892. Divided and this application filed May 5, 1913. Serial No. 765,518.

To all whom it may concern:

Be it known that I, JOHN C. LINCOLN, a citizen of the United States, resident of Cleveland, county of Cuyahoga, and State 5 of Ohio, have invented a new and useful Improvement in Methods of and Apparatus for Producing Sparkless Commutation, of which the following is a specification, the principle of the invention being 10 herein explained and the best mode in which I have contemplated applying that principle, so as to distinguish it from other inventions.

My invention relates to methods of and 15 apparatus for producing sparkless commutation, its object being to increase the efficiency of electric apparatus in which commutation occurs by the elimination of the sparking which usually attends such action.

20 The said invention consists of a method and apparatus hereinafter fully described and particularly set forth in the claims.

The annexed drawing and the following description set forth in detail certain means 25 embodying the apparatus forming a part of my invention, the disclosed means, however, constituting but one of various mechanical forms in which the principle of the invention, both as relates to the method and 30 means, may be applied.

This application furthermore constitutes a division of my application, Serial No. 674,892, filed Feb. 2, 1912.

In said annexed drawing, the figure is a 35 diagrammatical representation of a dynamo electric machine arranged in accordance with my invention and shown as being applied for use in connection with welding or repairing of castings.

40 In illustrating that part of my invention directed to the apparatus and serving as one form of apparatus for carrying out my improved method, I have chosen the transformer illustrated in the figure. This transformer 45 former comprises a central rotatory armature A, a field structure B, and a circuit J arranged so that the current therein may be applied for the purpose of welding or repairing castings, in the manner fully de-

scribed in my above-mentioned pending application. The armature is drum-wound and of full pitch. 50

This field structure is provided with four poles, each of which is divided into two parts, a part C of lesser cross-section, and 55 a part C' of greater cross-section. The pole-portions C' of greater cross-section have two field windings upon them, a winding D of comparatively high resistance and a winding E of comparatively low resist- 60 ance. The pole-portions C of smaller cross-section have wound upon them windings D' of resistance similar to that of the windings D, in series with the latter and connected with the main brushes F and F'. These 65 windings D and D' are therefore connected in shunt in the apparatus.

The windings E of low resistance are in 70 series with each other, a secondary brush G and an exterior arc circuit J. This secondary brush is located so as to be intersected by a plane passing through the axis of the armature A and midway between the two pole-portions C and C'. The direction 75 of the various currents in the field windings are indicated by the arrows, in the figure.

The direction of rotation of the armature and the direction and arrangement of the windings on the two pole-portions of each 80 complete pole-piece are such that the polarity of the armature pole produced at the secondary or arc-brush G will be of the same sign as that of the divided pole-piece adjacent to which this brush is located. These 85 two pole-portions I furthermore arrange so that they will be separated by a considerable distance as shown in the figure, and the respective zones of the generating and motor-windings of the armature will meet in a 90 plane passing through the axis of the armature and through the secondary brush, that is between, and substantially midway between, the inner extremities of these pole-portions. The position of such brush will 95 therefore define the rear of the zone of the generating windings. The pole-portions C and C' are provided with windings such as will, as before stated, make them poles of

the same sign. That part of the armature subtended by the brushes F' and G carries the generated current and that part subtended by brushes F and G carries the 5 motor-current. That direction of rotation of the armature is now selected which, as also before stated, will make the pole formed in the armature at the arc-brush G, of the same sign as that of pole-portions C and 10 C'. In the machine illustrated this sign is N. In order therefore to produce an N-pole at brush G, the direction of current in the generating armature coils must be up, as illustrated, and the direction of the current, 15 in that part of the armature coils carrying the motor current, must be down, also as illustrated. The direction of rotation of the armature in the illustrated example must therefore be that indicated by the arrow. 20 It will be recognized by those skilled in the art that a brush in the position of brush G will at no load tend to spark, due to over commutation. The gap between the two pole-portions is sufficiently great so that the 25 tendency dies not result in actual sparking. Now as the load comes on, this arrangement will tend to weaken the two stationary field-poles and therefore create a magnetic field through which the armature winding passes 30 at the instant of short-circuit which is weaker as a result of which the voltage in the coil or coils short-circuited by the arc-brush at the instant of short-circuit, will therefore at a certain stage of increase of 35 the load be reduced to a point which will produce perfect commutation.

In carrying out my invention in practice, I have found that substantially sparkless 40 commutation is obtained in a transformer having an armature of $16\frac{1}{4}$ " diameter, by making the air-gap between the poles and the armature $\frac{3}{16}$ ", and making the space between the inner ends of the pole portions $2\frac{3}{4}$ " in width. Practical experience in building 45 these transformers has shown that in order to obtain this sparkless commutation according to my invention, the distance to be selected as separating the pole-portions should be substantially the same, in any 50 given transformer, as would be selected for the minimum distance for separating dis-

similar poles in an ordinary dynamo-electric machine of similar mechanical dimension.

Having fully described my invention, what I claim and desire to secure by Letters Patent is:—

1. The method of securing substantially sparkless commutation in a divided-pole drum wound dynamo-electric machine, which consists in withdrawing current from the armature coils at a point intersected by a plane passing between two pole-portions and through the armature's axis, and causing that direction of armature rotation which will make the polarity of the same 65 sign as that at each of said two pole-portions.

2. The method of preventing sparking in a rotary transformer having a divided pole, a drum-wound armature, main brushes and 70 an intermediate current-collecting brush, which consists in causing such direction of rotation as will produce at the said intermediate brush, a polarity of the armature pole of the same sign as the polarity of the 75 two pole portions.

3. The method of preventing sparking in a rotary transformer having a divided pole, a drum-wound armature, main brushes and 80 an intermediate current-collecting brush which consists in causing a direction of rotation and polarity of poles such that the armature reaction will tend to weaken the stationary poles.

4. In a rotary transformer, the combination of a drum-wound armature; a suitable commutator; means for creating a magnetic field and including divided poles; main brushes and an intermediate brush; the 85 windings of said pole portions, armature and connections being arranged so that the direction of rotation will be such that the generated current will produce a pole in the armature of the same sign as the adjacent field pole pieces. 90 95

Signed by me, this 16th day of April, 1913.

JOHN C. LINCOLN.
